CUT-OFF VALVE.

No. 286,002.

Patented Oct. 2, 1883.

UNITED STATES PATENT OFFICE.

THADDEUS W. HEERMANS, OF CHICAGO, ILLINOIS.

CUT-OFF VALVE.

SPECIFICATION forming part of Letters Patent No. 286,002, dated October 2, 1883.

Application filed March 5, 1883. (No model.)

To all whom it may concern:

Be it known that I, THADDEUS W. HEERMANS, residing at Chicago, in the county of Cook and State of Illinois, and a citizen of the 5 United States, have invented a new and useful Improvement in Cut-Off Valves for Steam-Engines, of which the following is a full description, reference being had to the accompanying drawings, in which—

10 Figure 1 is a cross-section on line *x* of Fig. 4; Figs. 2 and 3, longitudinal and cross sections of a cylindrical valve; Fig. 4, a longitudinal section on line *y* of Fig. 1; Figs. 5, 6, and 7, details of the device for giving the 15 valve-rod an endwise movement, and Fig. 8 a side view of the arm used in rocking the valve-rod; Fig. 9, supporting-plate for the rod *J*.

The object of this invention is to improve the construction and operation of a steam-engine; and its nature consists in the several improvements in parts and combination of parts 20 hereinafter described and claimed as new.

In the drawings, *A* indicates the cylinder; *B*, its heads; *C*, piston-rod; *D*, steam-chest; 25 *E*, cylindrical valve-casing; *F*, cylindrical valve; *G*, exhaust passage or pipe; *H*, exhaust; *I*, cap-plate of steam-chest; *J*, valve-rod; *K*, arm for giving the valve-rod its endwise movement; *L*, guide-bracket; *M*, guide; 30 *N*, support for the valve-rod and rocking arm or lever; *O*, stuffing-boxes; *P*, steam-pipe; *a*, steam-chamber, partly surrounding the valve-casing *E*; *b*, openings or ports in the casing *E*; *c d*, openings or ports in the valve *F*; *e*, 35 steam and exhaust ports for the cylinder; *f*, exhaust-passages in bonnet; *g*, adjustable stops or collars on the rod *J*; *h*, supporting-plate for the rod *J* at or near the rocking arm *i*; *j*, upper end of arm *i*; *k*, spline for communicating 40 a rocking motion by the arm *i* to the rod *J*; *l*, screw for clamping the collars *g* to the rod *J*; *m*, pin or bolt for attaching an eccentric-rod; *n*, rod for rocking the arm *i*. The cylinder 45 *A*, with its heads, contained piston, and piston-rod, are so nearly of the usual construction as not to require a specific description. The steam-chest is cylindrical in so far as it is 50 separate from the main cylinder, except at the top, which is covered by the plate *I*. The cylinder and steam-chest are cast together, as shown at Fig. 1, the steam passages and ports

being cored out in the usual manner, and by surrounding the valve-cylinder *E* with the steam-passage *a*, I prevent the valve *F* from sticking by expansion.

55

The valve *F* is of a sufficient length to cover the steam-ports, as shown in Fig. 4, and as shown enlarged at Fig. 2. It will be seen that its ends are solid, and that it has a middle partition, so that at each end it has a separate 60 and distinct action. Near its ends it is cut through to form the ports *d*, as shown in Figs. 2 and 4. It is also provided with the ports *c*, which operate in connection with the ports or passages *b* of the valve-cylinder *E*. The long 65 cylindrical valve *F* has a compound movement—that is, a sliding and rotary motion—communicated to it by the arms *K* and *i* through the rod *J*. The arm *K* is attached to the rod by means of two adjustable collars or 70 clamps, *g*, which are fastened to the rod *J* each side of the arm *K* and in close contact therewith. These collars are of the form shown in Fig. 7, and are clamped to the rod by the screw or bolt *l*, and, as they may be moved 75 along the rod, they furnish the means for adjusting the endwise position of the valve *F*, and also for taking up or compensating any wear.

The rod *J* passes through the end of the arm 80 *K*, as shown in Fig. 6, and while the collars *g* are fastened to the rod *J* it is free to rotate in that part of the arm through which it passes, so that the upper end of the arm in giving the rod its endwise movements will not interfere 85 with the rocking or rotating of the valve-rod. The arm *K* is supported by the guide or rod *M*, which is connected with the bracket *L*. This arm *K* is operated by an eccentric from the main shaft in the usual manner, having 90 its rod attached to the pin or bolt *m*.

Near the arm *K*, I apply another arm, *i*, to the shaft *J*, which arm is supported by the bracket *h* *N*, which is suitably attached to the frame or support of the engine or main 95 shaft. This device is arranged so that the rod *J* will pass freely through it, and thus prevent its interfering with end movements; but it is provided with a groove, and the arm *i* is also provided with a similar groove, (shown 100 at *k* in Fig. 8.) The spline is placed in these grooves loosely, so that while it will prevent

the arm *i* from rotating around the shaft it will not interfere with its end movements. The key or spline is prevented from working out by the bracket *h N*. The end *j* of the arm 5 *i* is connected with the cut-off eccentric by the rod *n*; but I do not limit myself to this means for giving the arm *i* a reciprocating movement for rocking the valve *F*. The connection of the arm *i* with the eccentric or other 10 device may be made adjustable, so that the rocking movement may be regulated or adjusted.

By this arrangement for supporting and operating the valve-rod the valve *F* is given a 15 twisting or spirally-rotating motion, whereby the ports or openings *c* are made to operate by the rocking movement of the valve, while the ports *d* and the exhausts are controlled and operated by the endwise movement of the 20 valve, and by this arrangement I am enabled to operate all of the ports or openings by the use of a single valve, thereby reducing the 25 number of parts and simplifying the construction of the steam-chest and its ports, and the spiral movement of the cylindrical valve, combined with the endwise movement, gives all 30 of the ports an easy and prompt action, while the valve itself is perfectly balanced in both of its motions and relieved from friction or 35 other difficulties in the way of its prompt and efficient action; also, a simple and efficient independent cut-off is produced in a single device having two distinct and independent motions, or a valve which may be used for admitting and exhausting steam separately from or independent of the cut-off.

This valve can be used on all classes of engines and as an automatic or adjustable cut-off, and as both of its motions are positive and 40 occur continuously at each stroke of the valve it is applicable to high and low speed engines, and by its use and arrangement I am able to keep exhaust-steam from contact with the live-steam spaces.

It will be seen from the foregoing that the 45 rocking and endwise movement of the valve are continuous and occur at each of its strokes, which is an entirely different thing from those engines wherein the valve is connected with a governor, so that an increase in the speed of 50 the engine causes the governor-arms to fly outward, and thereby partially rotate a longitudinally-movable valve to reduce the inflow of steam to the cylinder.

What I claim as new, and desire to secure by 55 Letters Patent, is—

1. The cylindrical cut-off valve *F*, having imparted to it the simultaneous rocking and endwise movements continuously at each of its strokes, substantially as described. 60

2. The combination of the arm *i*, having the groove *k*, with the valve-rod *J*, having a corresponding groove, the loosely-fitting spline, the bracket *h N*, retaining the spline against longitudinal displacement, and the arm *K*, for 65 imparting continuous and simultaneous rocking and endwise movements to the valve *F* at each stroke of the piston, substantially as described.

3. The combination of the arm *i*, having the 70 groove *k*, with the valve-rod *J*, having a corresponding groove, the loosely-fitting spline, the bracket *h N*, retaining the spline against longitudinal displacement, and through which the valve-rod passes, and the arm *K*, secured 75 at one end to the valve-rod between the adjustable clamps *g*, and at its other end arranged on a guide, *M*, for imparting continuous and simultaneous rocking and endwise movements to the valve at each stroke of the piston, substantially as described.

4. The tubular or hollow valve *F*, having a middle partition, inclosed ends, and ports *c d*, substantially as described. 80

THADDEUS W. HEERMANS.
